tion, New York, N. Y., a corporation of New
York

Application August 9, 1945, Serial No. 609,792

5 Claims. (Cl. 101—91)

1

This invention relates to printing mechanisms generally but specifically to endorsing mechanisms for checks for selectively printing the partial or full endorsement on the checks passed through the machine.

This invention may be viewed as an improvement upon the check endorsing mechanism shown and described in the patent to S. Brand, No. 2,237,269, granted April 1, 1941, and especially upon the patent to A. E. Miller et al., No. 2,307,150, granted January 5, 1943.

The main object of the present invention is to provide a check endorsing mechanism which is capable of effecting two types of endorsement, either of which may be selected at the will of the operator. Such types of endorsement are utilized in connection with two different forms of check handling. One requires printing of the date and "bank number" and the other requires, in addition, the printing of other data identifying the bank clearing the check, etc.

Endorsing mechanism shown in the patent to A. E. Miller et al. previously cited is provided with selective means for controlling the operation of the endorsing mechanism in accordance with the compartments selected. Such selective devices, however, required their incorporation in the sorting machine by the user or a serviceman so as to vary the selective control of the endorsing mechanism according to the requirements. Such selective control, however, would not enable the discrimination between partial and full endorsement operations and if the machine was conditioned for one type of endorsing operation it was necessary for the operator to effect an additional manipulation to condition the machine according to another requirement. This mode of operation greatly slowed up the operation and it is to overcome this disadvantage that the present arrangement has been devised.

Another object of the invention is to provide a selective arrangement which, when set up by the operator, will carry out selective endorsing operations, either partial or full, according to the requirements and automatically without attention on the part of the operator.

A still further object of the invention is to enable the selective control of the partial and full endorsing mechanisms in accordance with the compartment selected and preferably under control of the compartment selecting keys.

A more specific object of the invention is to provide an electrical arrangement including selective plug connections which can be varied

by the operator at will so as to provide selective control of the partial and full endorsing mechanisms in accordance with the compartments selected.

5 A still more specific object of the invention is to disable the aforesaid selective control by the operator and to provide an additional operator control which enables continuous repeated operation of the partial endorsing mechanism or alternatively a continuous repeated operation of the full endorsing mechanism, whereby some checks sorted during one run may be either partially endorsed and others in another run fully endorsed.

10 15 Another object of the invention relates specifically to the construction of the check endorsing mechanism which is rugged in construction and efficient in operation and is considered to be a simplification over that previously devised.

20 25 Another object of the present invention is to devise the improved construction of the check endorsing mechanism so that it may be incorporated in existing machines without radical changes.

30 35 While the improvement has been shown in the combined accounting and check sorting machine of the type fully shown and described in the patent to Fuller et al., No. 2,079,442, granted May 4, 1937, many or all of the features of the present invention may be incorporated in other types of machines and the disclosure should be considered as merely illustrative and not restrictive.

40 45 Other objects of the invention will be pointed out in the following description and claims and illustrated in the accompany drawings, which disclose, by way of example, the principle of the invention and the best mode, which has been contemplated, of applying that principle.

In the drawings:

Fig. 1 is a view in side elevation showing the right side of the manually controlled check sorting machine to which the present improvements are preferably applied.

45 Fig. 2 is a wiring diagram of the electrical parts of the present apparatus.

Figs. 3a and 3b are details of the cams which effect partial and full endorsing operations.

50 Fig. 4 is a partial sectional view of the sorting drum showing particularly the normal relationship between the check feeding mechanism and check sorting compartments.

Fig. 5 is a sectional view taken on the line

Fig. 6 is a sectional view taken on the line 6—6 of Fig. 7.

Fig. 7 is a front elevational view partially in section taken on the line 7—7 of Fig. 6.

Fig. 8 is a plan view of the endorsing mechanism and coordinated mechanism of the manually controlled check sorting machine.

The present invention is preferably shown in connection with a check or document sorting machine, fully shown and described in Patent No. 2,079,442, dated May 4, 1937.

A sorting machine of this type is provided with a sorting drum 10 (Figs. 1 and 4) which is loosely mounted upon a shaft 11 (Fig. 1) and rotated by a chain 12 from a drive shaft 13 driven by a motor. The shaft 13 may be rotated in either direction to correspondingly rotate drum 10 to select a desired sorting compartment carried by the drum 10 by the shorter of the two directions of rotation. By means of compartment selecting keys 14, of which there is one for each compartment, the extent and direction of rotation of sorting drum 10 is predetermined and said keys control an electromagnetic stop mechanism, generally designated by numeral 15 in Fig. 1, which cooperates with lugs 16 carried by the drum 10 to stop the drum at the desired position. All of the means for carrying out the above functions are well known and fully described in the above cited patent.

In Fig. 4 there will be seen a portion of the sorting drum 10 and two of the sorting compartments 17. The checks or documents 18 to be sorted are taken from a pile and are individually inserted by hand in a feeding chute 19 between feeding rollers to be hereinafter described. The feeding operation is initiated by the depression of a motor release bar 20 (Fig. 1) and in the present machine effects the feeding of the check and the full or partial endorsing of the check or document.

Motor release bar

Check feeding operations are rendered operative when the motor release bar 20 is depressed. As best shown in Fig. 1, the motor release bar 20 is positioned exteriorly of the check and document sorting machine for a manual depression. When the motor release bar 20 is depressed it effects a clutch connection to drive a shaft 34, such clutch connection being effected by an electromagnetically controlled clutch which is fully shown and described in the patent to S. Brand, No. 2,237,269, granted April 1, 1941, and shown in detail in Fig. 2 of this patent.

Referring to Fig. 1, secured to the constantly rotating drive shaft 28 is a sprocket gear (not shown) around which passes an endless chain 29 surrounding a sprocket gear 30 attached to a shaft 31. Attached to said shaft 31 is a pinion 32 meshing with a gear 33 loosely mounted on the shaft 34. Depression of the motor release bar will effect a clutch connection between the gear 33 and the drive shaft 34 to effect a complete rotation of the latter to perform functions now to be described.

Check feeding mechanism

After the drum 10 has been positioned according to the compartment selecting key 14 operated, the check 18 to be sorted with or without an endorsing operation is manually inserted in the aperture 19 (Fig. 4) and the motor release bar 20 is then depressed to cause it to feed the inserted check into the selected compartment by feeding means now to be described.

Attached to the shaft 34 (Fig. 4) is a gear 35 in mesh with a gear 36 loose on a fixed stud 37 (see also Fig. 8), which gear drives a gear 38 loose on a fixed stud 39. The gear 38 meshes 5 with a gear 40A attached to one end of a drive shaft 41 and the other end of the drive shaft 41 has also attached similar gear 40B (Fig. 8). Gear 40B meshes with an idler pinion 42 (Fig. 4). Said idler pinion 42 meshes with a pinion 44 attached to a feed roller shaft 45. The pinion 44 meshes with a pinion 46 attached to a feed roller shaft 47. To the feed roller shafts 45 and 47 there is secured the small feed rollers 48.

Fixed in the main side frames of the machine 15 is a transverse casting 50 (Figs. 6 and 8) which carries side frame plates 51 and 52 (Fig. 8) and in these side frame plates are journaled the drive shaft 41 and also the feed roller drive shafts 45 and 47 (Fig. 4). Attached to the drive shaft 41 20 is a plurality of resilient feeding rollers 53 (Figs. 3 and 8).

The casting 50 has a plurality of integral ears 54 (Fig. 8) which supports a transverse rod 55 (Figs. 7 and 8) and dependently hung from rod 55 but clamped thereto at one side of the check endorsing mechanism is a plurality of arms 56 in which is journaled the feed roller drive shaft 57 carrying feeding rollers 58 which cooperate with the related feeding rollers 53. At the other side 30 of the check endorsing mechanism is a pair of arms 59 similar to the arms 56 which are dependently hung from the rod 55 but clamped thereto and carry at their lower ends a feed roller driving shaft 60 having attached thereto feed 35 rollers 61, cooperating with the related ones of the feeding rollers 53. The gear 40A meshes with a gear 62 (Fig. 8) attached to the feed roller driving shaft 60 and the gear 40B meshes with a gear 63 (Fig. 8) attached to the feeding roller driving shaft 57. Hence, it is obvious that the feeding rollers 53 are oppositely driven with respect to the feeding rollers 58 and 61.

The check to be fed is inserted between the bite 64 (Figs. 4 and 8) of the aforementioned feeding rollers 53, 58, 61. The arms 56 and 59 have, as shown in Fig. 8, split hub portions surrounding the rod 55 and by clamping screws 65 the arms may be angularly set in the desired position so that the feeding rollers 58 and 61 cooperate with the feeding rollers 53. If so desired the arms 56 and 59 may be loosely mounted on the rod 55 and any suitable spring means may be provided to rock the rollers 58 and 61 into resilient cooperation with the feeding rollers 53.

The smaller feeding rollers 48 and the larger feeding rollers 53, 58 and 61 are similar to those provided in the check feeding mechanism in the patent to S. Brand, No. 2,237,269 but in the patented construction the corresponding feed roller drive shafts 41, 57, 60 and the feed roller shafts 45 and 47 for the smaller feed rollers are mounted upon a reciprocable frame but in the present construction all of said feed roller shafts have a fixed bearing, due to the manner in which they are supported by the casting 50.

When checks are to be sorted they are manually inserted between the bite 64 of the feeding rollers 53, 58 and 61 and as the check is fed by said rollers and the leading edge emerges therefrom it passes between the bite of the feeding rollers 48 which are concurrently driven and the latter will continue to feed the check to completely feed it to the selected compartment 17. The feed roller driving shafts are driven to such an extent that if the check is of normal width 75 they will completely feed a check which has been

inserted in the chute 19 to the selected compartment 17 when the check feeding is initiated by the depression of the motor release bar.

So far described the check feeding arrangement is somewhat similar to that disclosed in the patent to S. Brand, No. 2,237,269, except for the mounting of the feed roller driving shafts.

Endorsing mechanism

It is desirable to selectively endorse certain checks which are disposed in selected sorting compartments and a further feature of the machine enables endorsing operations to be effected according to "partial endorsement" or "full endorsement."

Endorsing operations are effected on the checks by means of a segmental printing cylinder designated generally by numeral 70 in Figs. 5 and 7. The segmental printing cylinder comprises an arcuate shaped segment member 71 and integral side plates 72. Said side plates 72 are provided with split hub portions 73 so that by clamp screws 74 the segmental printing cylinder is fixedly attached to a driving shaft 75. Between the side plates 72 there is journalled a rod 76 on which are pivoted printing wheels consisting of groups 77 and 78. The wheels 77 comprise four settable printing wheels which print the day of the month, the month, and the year. The settable wheels 78 are numeral wheels adapted to print a "block number" and such wheels are set to print the same number on a group of checks sorted in selected compartments until changed. Cooperating with the groups of printing wheels 77 and 78 are spring pressed aligning pawls 79 which maintain the printing wheels in their set positions. The print wheels 77 and 78 project through a notch 80 in the segmental plate 71 and also through an aperture 81 of an electroplate 82 fixedly attached to the segmental plate 71. Such electroplate has printing characters for printing certain information upon the check which identifies the bank making the endorsement. When a full endorsement of a check is to be printed, printing is effected both from the electroplate 82 and the printing wheels 77 and 78 but when the check is to receive a partial endorsement, printing is effected only from the printing wheels 77 and 78.

Referring to Fig. 7 secured to the driving shaft 75 is a gear 83 meshing with a gear 84 loosely mounted upon the rod 55 and having a sleeve connection 85 with a gear 86, said sleeve also being mounted on the rod 55. Gear 86 meshes with a gear 87 secured to the feed roller driving shaft 60. Obviously, since shaft 60 rotates for each check feeding operation the driving train consisting of gears 87, 86, 84, 83 will invariably rotate the endorsing cylinder driving shaft 75 but whether or not endorsing operations will take place will depend upon the position of the frame which carries the endorsing cylinder. The driving shaft 75 is carried as shown in Figs. 6 and 7 by arms 88 and 89 which are loosely pivoted upon the rod 55 and in the normal position of the frame it will be seen (see Fig. 6) that the driving shaft 75 is eccentric with respect to the axis of the shafts 57 and 60 of the feeding rollers 58 and 61, the shaft 75 being normally in such position that while the printing cylinder is rotated during a check feeding operation none of the printing elements thereof will make contact with a rubber impression platen 90 which is the width of the printing cylinder (Fig. 8). The rubber impression platen 90 is carried by a pair of arms

91 pivoted on a rod 92 (see Fig. 4). For non-endorsing operations the endorsing cylinder frame 88-89 is maintained in the position shown in Fig. 6 by means now to be described.

Non-endorsing operations

Loosely pivoted upon the rod 55 and between the side frame plates 88, 89 of the printing cylinder frame is a casting which consists of a transverse bar 92 (Figs. 6 and 7) and a pair of upstanding bracket arms 93 and 94 loosely pivoted on shaft 55. A rod 95 is journalled in the bracket arms 93 and 94 and carries a follower roller 96. Also mounted on the rod 95 is a follower roller 97 which is capable of being shifted to the left (Fig. 7) for full endorsement and to the right for partial endorsement as will be later described, but for non-endorsing operations said roller 97 remains in the position shown in Fig. 7 for co-operation with a concentric disk 98 (see Fig. 6) secured to a drive shaft 103. Springs 99 (Fig. 6) are connected between the upper extremities of the side frame plates 88 and 89 to stationary studs 100 carried by brackets 104, 105 extending upwardly from the casting 50, thus causing studs 101 (Fig. 7) carried by each of the side frame plates 88 and 89 to bear against the related bracket arms 93 and 94. Thus, by this arrangement the tension in the springs 99 rocks the casting 92, 93 and 94 clockwise (Fig. 5) about the rod 55, causing the roller 97 to continuously bear against the concentric disk 98. The shaft 103 which carries the disk 98 is a cam driving shaft and is journalled in brackets 104, 105 and has secured at one end a gear 102 (Figs. 6 and 8) meshing with the gear 84. Hence, shaft 103 is rotated a complete revolution for each check feeding operation. The disk 98 with which the roller 97 cooperates is concentric in its complete periphery and understanding that the springs 99 attempt to rock the printing cylinder frame clockwise (Fig. 6) it is obvious that the co-operation of the follower roller 97 with disk 98 in a non-endorsing operation will cause the printing cylinder frame to remain in the position shown in Fig. 6 so that while said printing cylinder rotates it will not make contact with the platen 64 and hence no endorsement will be effected on the back of the check which is being fed to a selected compartment.

Full endorsement printing operations

As premised hereinbefore the machine may be conditioned so that during check feeding operations a "full endorsement" printing operation can be effected on the check and such printing is made on the back of the check from both the groups of printing wheels 77 and 78 and also the electroplate 82. In general, the machine is conditioned for full endorsement printing operations by shifting the roller 97 so that it is out of co-operative relationship with the concentric disk 98 (Fig. 8) thus enabling the roller 96 to cooperate with and follow the contour of the full endorsement printing controlling cam 110 (Fig. 3b) which is also secured to the cam driving shaft 103. The contour of the cam 110 is such as shown in Fig. 3b that it will enable the rocking of the printing cylinder frame to cause during the rotation of the printing cylinder the electroplate 82 and printing wheels 77, 78 to be impressed against the check to be endorsed as it is fed to the selected compartment. The movement of the roller 97 out of coaction with cam 98 is effected 75 by the energization of a solenoid 111F (Fig. 8)

which is energized and maintained energized previous to a check feeding operation by electrical circuits to be subsequently described. Energization of solenoid 111F will attract a core 112 (Fig. 6 and 8) and upstanding from the core 112 is a pin 113 which passes through an actuating plate 114 which is pivoted on a pin 109 which is an integral part of a support rod 108 fixed to casting 50. Also passing through the actuating plate 114 is a pin 115 which extends from the core 116 of the solenoid 111P, which latter solenoid is energized to condition the machine for partial endorsing operations. The actuating plate 114 has a slot receiving a pin 106 carried by a rod 117 which is slidable in the bracket arms 93, 94. As best shown in Fig. 7, clamped to the rod 117 by a clamp screw 118 is a member 119 having integral spaced arms 120 and 121 apertured to receive the rod 95, and between which arms 120, 121 the roller 97 is confined. Obviously, when rod 117 is shifted to the left as viewed in Fig. 7 and to the right as viewed in Fig. 8, roller 97 will be brought out of coaction with cam 98 which relationship is necessary for full endorsement operations.

Referring to Fig. 8 pivoted on the stud 115 are arms 123, 124 in a scissors arrangement, and extending between the free ends of arms 123 and 124 is a normally tensioned spring 125, the tension of this spring adapted to bring the free ends of the arms together so as to abut the stud 113 which, it will be recalled, extends from the core 112 of solenoid 111F.

When the solenoid 111F is energized prior to a check endorsing operation it will attract its core 112 and since pin 113 passes through the actuating plate 114 it will rock the latter clockwise about pivot pin 109 which is relatively stationary, thereby shifting pin 106 and rod 117 to the right to bring roller 97 to the right as viewed in Fig. 8 or to the left as viewed in Fig. 7 out of coaction with cam 98. Since the stud 113 bears against the arm 123 it is obvious that movement of the core 112 within the solenoid 111F will rock the arm 123 to tension spring 125. As will be clearer later on, solenoid 111F is maintained energized during the check feeding operation and the release of the key which selects the solenoid 111F for energization by the depression of another key prior to the next check feeding operation will deenergize the solenoid 111F, thereby enabling spring 125 to be effective to restore the core 112 outwardly, at the same time rocking the actuating plate 114 reversely, counterclockwise, again shifting rod 117 to the left as viewed in Fig. 8 or to the right as viewed in Fig. 7 to again cause roller 97 to coact with the concentric disk 98. Obviously, the scissors arrangement just described is provided to normalize or centralize the parts.

Partial endorsing operations

In general, the machine is conditioned for partial endorsing operations by the energization of the solenoid 111P caused by the depression of a compartment selecting key. In this case, the rod 117 is shifted to the left as viewed in Fig. 8 or to the right as viewed in Fig. 7 so that roller 97 now coacts with a cam 126 secured to the cam driving shaft 103. The profile of this cam is such that a scalloped portion thereof 126a (Fig. 3a) enables the rocking of the printing cylinder frame only at the time that the groups of printing wheels 77 and 78 are passing through printing position or in other words, cam 126 maintains the

printing cylinder out of printing operation during the time that the electroplate 82 is passing through the printing position so that printing therefrom cannot be performed.

When solenoid 111P is energized by the depression of a compartment selecting key related to a compartment which is to receive a check having a partial endorsement, it will attract its core 118 inwardly, rocking the actuating plate 114 about the pin 109 as a pivot shifting pin 106 and the rod 117 to the left as viewed in Fig. 8, to the right as viewed in Fig. 7, so that roller 97 now coacts with cam 126 prior to the check feeding operation. The rocking of actuating plate 114 will cause its stud 113 to rock the arm 124 to tension spring 125 and this tension of the spring is effective as previously described to centralize the parts after the deenergization of the solenoid 111P.

It is explained that during this operation the roller 96 still coacts with the full endorsement printing cam 110 but the roller will be unable to drop to the low portions of the cam 110, due to the fact that the corresponding higher portions of the cam 126 are dominant (see Figs. 3a, 3b).

For adjusting spring 125 to the desired tension, attached to the casting 50 is a stud 127 (Figs. 6 and 8) having a flattened extension 128. The rod 127 may be turned to such a position so that by the flattened extension 128 bearing against the extremity of the scissors arms 123 and 124, the relationship of the latter with respect to the stud 113 and the tension of the spring 125 may be readily adjusted. The desired position of the rod 127 is maintained by a nut 129 (Fig. 8) which fastens the rod 127 to the casting 50.

Conditioning of machine for selective full and partial endorsing operations

As previously indicated, the normal condition of the machine is such that unless the machine is conditioned for partial or full endorsing operations checks passing through into selected compartments will not be endorsed. By an electrical arrangement shown in Fig. 2 the machine may be conditioned so that checks sorted into certain compartments may be partially endorsed, other checks into other compartments may be fully endorsed and conversely all checks may be partially endorsed or all other checks may be fully endorsed.

The keyboard of the machine consists of four rows of six keys each. In view of the duplicate arrangement, only one row of keys is shown in Fig. 2. The compartment selecting keys 14 are depressed prior to operation of the motor release bar and as fully shown and described in Patent No. 2,079,442, each key when depressed is held depressed by a latch plate 134 in a well known manner. Keys 14 besides having contacts for determining the operation of the electromagnetic stop mechanism 15 have in the present machine supplemental contacts 135, one side of which is connected to the line side 136 and the other to plug sockets 137. Plug connections may be made 55 in such plug sockets 137, such as plug connection 138 to complete a circuit through the R2 relay and switch S1 to the other line side 139 or alternatively a plug connection 140 to complete circuit to the R1 relay through switch S1 to line 139. Therefore, dependent upon whether the key should cause a partial endorsement or a full endorsement the respective plug connections 140 and 138 are made. R1 relay when energized closes its contacts R1A to complete an obvious circuit through switch S4 to the solenoid 111P and R2

relay when energized closes its contacts R2B to complete an obvious circuit through the S5 switch to the solenoid 111F. By the above circuit arrangement selective plug connections may be made so as to determine the type of endorsement to be made on checks disposed in selected compartments. Solenoids 111P and 111F are retained energized because the key operated contacts 135 are closed until another key on the keyboard is depressed which shifts the latch plate 134, releasing the previously depressed key.

Although the machine may be selectively conditioned for partial and full endorsement operations by suitable plug connections 138 and 140, it may be desirable at times to eliminate all endorsing operations which, in the present machine, is effected by the opening of the switch S1.

At other times irrespective of the conditioning of the machine for both partial and full endorsing operations, it may be desirable to partially endorse all checks passing through the machine. This is done by opening switch S5 and closing switch S2. At other times full endorsement of all checks may be desirable which is performed in the present arrangement by opening switch S4 and closing switch S3. In either of the last two arrangements it is obvious that when these selective operations are performed switch S1 should be open.

Inking mechanism

Any suitable means may be provided for inking the electrophore 82 and printing wheels 77 and 78 and preferably comprises an inking roller 130 which is saturated with ink and which is mounted on a rod 141, dependently hung by arms 142. Pivoted on a stud 143 carried by an extension 144 of the arms 88 and 89 is a plate 145 and extending between a stud carried by the plate 145 and the lug extension 146 of the arms 142 is a spring 147, the tension and angle of the spring rocking the roller 140 to such position that it will re-ink the printing elements during the rotation of the endorsing cylinder. The arms 142 and related members 145 have a pin and slot connection 148. Adjustment of the inking roller so as to be in position to efficiently ink the inking elements is provided by an adjustable plate 149 pivoted on the stud 143 and by means of a headed screw 150 the desired adjustment may be provided. The construction is such that the inking roller supporting means may be rocked to the right as viewed in Fig. 6 to provide easy detachment of the inking roller 140.

While there have been shown and described and pointed out the fundamental novel features of the invention, it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. In a check endorsing machine for selectively endorsing checks with a full endorsement or partial endorsement, the combination of endorsing means comprising a rotatable endorsing cylinder carrying printing elements at the peripheral surface of said cylinder for printing a partial endorsement and supplemental printing elements also at the peripheral surface of said cylinder which, in conjunction with the first named printing elements, effect a full endorse-

ment, a platen between which and the printing elements of said endorsing cylinder the checks pass and are printed thereby, a plurality of different cam means selectively operative during the rotation of said cylinder, one to effect a relative movement between said platen and cylinder to cause a printing relationship between the first named printing elements and said platen to cause a partial endorsement on a check being fed, and the other to effect a relative movement between said cylinder and said platen to cause the first named and supplemental printing elements to print a full endorsement on a check, and selective means to render either of said plurality of different cam means effective.

2. In a check endorsing machine for selectively endorsing checks with a full endorsement or partial endorsement, the combination of endorsing means comprising a rotatable endorsing cylinder carrying printing elements at the peripheral surface of said cylinder for printing a partial endorsement, and supplemental printing elements also at the peripheral surface of said cylinder which, in conjunction with the first named printing elements, effect a full endorsement, a platen between which and the printing elements of said endorsing cylinder the checks pass to be printed thereby, a plurality of different cam means selectively operative during the rotation of said cylinder, one when rendered effective to effect relative movement between said platen and cylinder to cause a printing relationship between the first named printing elements and said platen to cause a partial endorsement on a check being fed, and the other when rendered effective to effect a relative movement between said cylinder and said platen to cause the first named printing elements and the supplemental printing elements to print a full endorsement on a check, selective means to render either of said cam means effective, a pair of partial and full endorsing control solenoids, and means controlled by each solenoid when energized to selectively render the related cam means effective.

3. In a check endorsing machine for selectively endorsing checks with a full endorsement or partial endorsement, the combination of a plurality of keys, endorsing means comprising a rotatable endorsing cylinder carrying printing elements at the peripheral surface of said cylinder for printing a partial endorsement, and supplemental printing elements also at the peripheral surface of said cylinder which, in conjunction with the first named printing elements, effect a full endorsement, a platen between which and the printing elements of said endorsing cylinder the checks pass to be printed thereby, a plurality of different cam means selectively operative during the rotation of said cylinder, one when rendered effective to effect relative movement between said platen and cylinder to cause a printing relationship between the first named printing elements and said platen to cause a partial endorsement on a check being fed, and the other when rendered effective to effect a relative movement between said cylinder and said platen to cause the first named printing elements and the supplemental printing elements to print a full endorsement on a check, selective means to render either of said cam means effective, a pair of partial and full endorsing control solenoids, means controlled by each solenoid when energized to selectively render the related cam means effective, and circuit closing means con-

trolled by certain of said keys to energize one solenoid and controlled by the other keys to energize said other solenoid.

4. In a check printing machine for selectively printing records with either of two different data, the combination of a plurality of keys, each of which when operated selects the data to be printed, endorsing means comprising a rotatable printing cylinder carrying printing elements for printing certain data, and supplemental printing elements which effect printing of other data, a platen, cam means for establishing a printing relationship between the first named printing elements and said platen to effect one data printing, and a different cam means establishing a printing relationship between the supplemental printing elements and said platen to effect another data printing, both of said cam means being selectively operative during the rotation of said cylinder, a pair of printing controlling solenoids to condition said preceding cam means to effect printing of either data, and means for energizing either solenoid including individual contacts operated and closed by each of said keys and selective wire connections to enable any key to energize any selected solenoid.

5. In a record endorsing machine for optionally effecting a partial or full endorsement of records, the combination of a rotatable endorsing cylinder carrying partial endorsing printing elements and supplemental printing elements which conjointly with said partial endorsing printing elements effect a full endorsement, a platen cooperating with the printing elements of said cylinder selected for printing, control means including a solenoid which is energized to cause the partial endorsing printing elements to cooperate with said platen to print a partial endorsement on a record, further con-

trol means including a second solenoid which is energized to cause the partial and supplemental printing elements to cooperate with said platen to print a full endorsement, a plurality of keys, contacts closed by the depression of said keys, variable plug circuit connections between said solenoids and the contacts closed by the keys to cause the energization of either of said solenoids by the depression of certain keys, a switch and circuit connections controlled thereby for retaining the first named solenoid continuously energized, and a supplemental switch, and circuit connections controlled thereby for retaining the second solenoid continuously energized, whereby partial or full endorsement can be effected on all records irrespective of the keys operated.
